Primary Examiner — Jennifer Rivard*Assistant Examiner* — Alison M Ofstun(74) *Attorney, Agent, or Firm* — Greer, Burns & Crain,
Ltd**CLAIM**

The ornamental design for a shaver, as shown and described.

DESCRIPTION

FIG. 1 is a top perspective view of the present shaver;
FIG. 2 is a left side view of the shaver of FIG. 1;
FIG. 3 is a right side view of the present shaver;
FIG. 4 is a front view of the present shaver;
FIG. 5 is a rear view of the shaver of FIG. 1;
FIG. 6 is a top view of the shaver of FIG. 1; and,
FIG. 7 is a bottom view of the shaver of FIG. 1.
In the drawings, the broken lines illustrate portions of the
shaver and form no part of the claimed design.

1 Claim, 5 Drawing Sheets(56)
